UNITED STATES PATENT OFFICE.

CARTWRIGHT J. EDNEY, OF SHAWNEE, OKLAHOMA TERRITORY, ASSIGNOR
OF ONE-HALF TO GEORGE H. KERFOOT AND WILLIAM S. MCMILLEN, OF
SHAWNEE, OKLAHOMA TERRITORY.

CHURN.

SPECIFICATION forming part of Letters Patent No. 724,269, dated March 31, 1903.

Application filed May 15, 1902. Serial No. 107,473. (No model.)

To all whom it may concern:

Be it known that I, CARTWRIGHT J. EDNEY, a citizen of the United States, residing at Shawnee, in the county of Pottawatomie and 5 Territory of Oklahoma, have invented a new and useful Churn, of which the following is a specification.

This invention relates to mechanical movements, and has for its object to convert swing- 10 ing or reciprocatory movements into rotary or oscillating movements, and is furthermore designed to provide an improved operating device which is particularly adapted for actuating churn-dashers.

15 A further object is to arrange the device so that it may be mounted upon the wall of a building or suitable upright support, so as to remain in a relatively fixed position, it being designed to apply and remove the churn-body 20 without removing or interfering with the operating device, as occasion may demand.

With these and other objects in view the present invention consists in the combination and arrangement of parts, as will be herein- 25 after more fully described, shown in the accompanying drawings, and particularly pointed out in the appended claims, it being understood that changes in the form, proportion, size, and minor details may be made within 30 the scope of the claims without departing from the spirit or sacrificing any of the advantages of the invention.

In the drawings, Figure 1 is a perspective view of a churning apparatus embodying the 35 features of the present invention. Fig. 2 is a longitudinal sectional view thereof. Fig. 3 is a detail sectional view showing the connection between the dasher-stem and the rotatable head.

40 Like characters of reference designate corresponding parts in all the figures of the drawings.

In carrying out the present invention there is provided a bracket or support consisting 45 of an upright back 1, preferably formed by a board or plank which is tapered upwardly and provided near its lower end with outwardly-directed vertically-aligned bracket-arms 2 and 3, respectively, which are braced

and strengthened by means of an upright web 50 or plate 4, secured to the back of the bracket and fitting snugly between the bracket-arms. The outer end portion of the upper arm is provided with a circular opening 5 to form a bearing, while the lower arm is slightly shorter 55 than the upper arm and has its outer end provided with a substantially semicircular notch or seat 6 to form a lower bearing. The back of the bracket is provided with a longitudinal series of perforations for the reception of suitable fastenings *a*, which project beyond the back and form means for securing the bracket to an upright support, as clearly indicated in Fig. 2 of the drawings.

An upstanding cylindrical rotatable head 7 65 is mounted between the two bracket-arms and is provided at its upper end with a reduced journal 8, which is mounted in the bearing 5, while its lower end portion is provided with a circular groove 9 to form a reduced intermediate journal 10, which fits within the semi-circular bearing 6 in the lower bracket-arm, there being a bearing-cap 11 secured to the outer end of the lower arm 3 and embracing the intermediate journal of the head, so as to 75 hold the latter in place. The lower end of the head, which projects a suitable distance below the lower bracket-arm 3, is provided with a longitudinal socket or seat 12 and a longitudinal notch or slot 13, formed in one 80 side of the head and communicating throughout its entire length with the seat, and a transverse opening 14 extends entirely through the lower end of the head and pierces the seat therein.

85 The dasher comprises a stem 15 and a plurality of rods or bars 16, projected through transverse openings in the lower end of the stem and all lying in the same vertical plane. The upper end of the dasher-stem is fitted in 90 the seat or socket in the lower end of the rotatable head and is held therein by means of a headed pin or key 17, which passes through the opening 14 in the head and also pierces the stem. The pin also carries a horizontally-disposed fan 18, which is designed to work across the top of the churn-body, so as to prevent flies and other insects from settling 95

upon the top of the churn. To hold the pin against displacement, a nut 17^a may be used, as shown in Fig. 3.

Any ordinary form of churn-body, either a stone crock, a metal can, or a wooden bucket, may be employed, and therefore it has not been deemed necessary to illustrate any particular form of churn-body, as it forms no part of the present invention.

10 For manipulating the rotatable head there is a vertically-disposed approximately triangular oscillatory operating-frame composed of a pair of downwardly-converging arms or bars 19, which are pivotally connected to the 15 upper end of the back of the bracket 1 by means of a single pivot-pin 20, the lower end portions of the arms being braced and connected by a cross-bar 21, which lies just above the bracket-arm 2, thereby forming a 20 substantially A-shaped swinging frame. The operative connection between the swinging arms and the rotatable head is afforded by means of the cords 22 and 23, respectively, which have their inner ends connected to the 25 respective upper and lower ends of the head and their outer ends connected to the lower end portions of the swinging arms. The outer end of the cord 22 is connected to the lowermost extremity of the adjacent arm, 30 while the cord 23 is connected at a distance from the lower end of the arm, so that the portion of the arm below the cord 23 forms a handle for manipulating the operating device. As the bracket-arms 2 and 3 lie in the 35 path of the swinging arms 19, the former arms form stops to limit the movement of the swinging frame formed by the arms 19 and the cross-bar 21.

What I claim is—

40 1. In a churn, the combination of a bracket comprising a vertical back designed to be se-

cured to a wall or other support, and horizontal arms extending outward from the lower portion of the bracket and provided with bearings, a rotatable head journaled in 45 the bearings of the arms and disposed vertically between the same and depending from the lower arm, a vertically-disposed approximately triangular oscillatory frame composed of converging bars pivoted at their upper 50 ends to the bracket at the top of the back thereof and located at opposite sides of the horizontal arms, a rod connecting the bars and located above the said arms, a flexible connection wound around the rotatable head 55 at a point between the horizontal arms and connected with the bars of the oscillatory frame, and means located below the arms for the attachment of a dasher-shaft, whereby the dasher-shaft and the churn-body may be 60 removed without detaching the operating mechanism, substantially as described.

2. The combination with a rotatable member having a longitudinal socket in its lower end and a longitudinal slot communicating 65 with the socket and opening through the lower end of the member, of a dasher-stem having its upper end fitted in the socket and insertable and removable through the slot, a fan applied substantially radially across the 70 lower end portion of the rotatable member at a point below the top of the stem, and a removable fastening piercing the fan, the rotatable member and the stem.

In testimony that I claim the foregoing as 75 my own I have hereto affixed my signature in the presence of two witnesses.

CARTWRIGHT J. EDNEY.
